UNITED STATES PATENT OFFICE.

THOMAS A. CONLON, OF SILVER SPRING, MARYLAND.

TRAVERSING MECHANISM.

Application filed February 17, 1926. Serial No. 88,959.

(GRANTED UNDER THE ACT OF MARCH 3, 1883; 22 STAT. L. 825.)

The invention described herein may be used by the Government, or any of its officers or employees in prosecution of work for the Government, or by any other person in the United States, without payment to me of any royalty thereon, in accordance with the act of March 3, 1883.

This invention relates to a traversing mechanism especially applicable for guns. In those types of guns wherein the center of gravity of the piece is located forwardly of the center of rotation considerable difficulty has been experienced in traversing the gun. In addition, if the carriage wheels are out of level the load on the traversing hand wheel is excessive.

The principal object of the present invention is to provide a traversing mechanism for guns of the above character in which clearance is maintained between the top and bottom carriage during traversing and which upon firing will transmit the load directly to the bottom carriage. These conditions are made to obtain through wide variations in limits of elevation by providing between the carriages a circular anti-friction bearing which is supported preferably by Belleville springs.

To these and other ends, my invention consists in the construction, arrangement, and combination of elements, described hereinafter and pointed out in the claims forming a part of this specification.

A practical embodiment of the invention is illustrated in the accompanying drawing, wherein:

Fig. 1 is a fragmentary longitudinal sectional view showing a gun mount equipped with a traversing mechanism constructed in accordance with the invention;

Fig. 2 is a fragmentary plan view of the bottom carriage with the bearing partly broken away; and

Fig. 3 is a sectional view on the line 3-3 of Fig. 2.

Referring to the drawings by numerals of reference:

There is shown a mount which includes a fixed bottom carriage 5 on which is rotatably mounted by means of a circular anti-friction bearing 6 a top carriage 7 in which is trunnioned a gun 8. In the present instance the center of gravity of the gun, at all angles within its range of elevation, is

forward of the pintle 7' so that as a consequence there is present a tendency of the top carriage to drag on the bottom carriage. To facilitate traversing of the top carriage, clearance is maintained between it and the bottom carriage by means of a plurality of Belleville springs 9 interposed between the bottom carriage and the roller race and mounted on fixed studs 10. It has been found in practice that better results are obtained when the Belleville springs 9 are suitably spaced according to requirements, but I do not limit the invention to such a disposition of the springs as excellent results are also obtained by a closer arrangement.

By this construction, a proper clearance will always be maintained between the top and bottom carriages irrespective of the displacement of the center of gravity on elevation of the gun or the level of the mount.

Upon firing the springs 9 are deflected and the load is transmitted directly to the bottom carriage.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. A mount for guns including a bottom carriage, a rotatable top carriage, a circular anti-friction bearing interposed between the carriages, a plurality of spaced Belleville springs supporting the bearing for normally maintaining clearance between the carriages but adapted to be deflected on firing so that the load may be transmitted directly to the bottom carriage, and studs for mounting the springs.

2. A mount for guns including a bottom carriage, a rotatable top carriage, a circular anti-friction bearing interposed between the carriages, and a plurality of spaced Belleville springs supporting the bearing for normally maintaining clearance between the carriages but adapted to be deflected on firing so that the load may be transmitted directly to the bottom carriage.

3. A mount for guns including a bottom carriage, a rotatable top carriage, a circu-

- lar anti-friction bearing interposed between the carriages, and a plurality of Belleville springs supporting the bearing for normally maintaining clearance between the carriages but adapted to be deflected on firing so that the load may be transmitted directly to the bottom carriage.
4. A mount for guns including a bottom carriage, a rotatable top carriage, an anti-friction bearing interposed between the carriages and resilient means supporting the

bearing for normally maintaining clearance between the carriages but adapted to be deflected on firing so that the load may be transmitted directly to the bottom carriage. ¹⁵

5. A mount including a bottom carriage, a rotatable top carriage, an anti-friction bearing interposed between the carriages, and resilient means supporting the bearing for maintaining clearance between the carriages during rotation of the top carriage. ²⁰

THOS. A. CONLON.
